CLARENCE D. HEDDEN, OF CORRAL, IDAHO.

EXTENSION-SWEEP BIT-BRACE.

1,266,802.

Specification of Letters Patent. Patented May 21, 1918.

Application filed October 2, 1917. Serial No. 194,380.

To all whom it may concern:

Be it known that I, CLARENCE D. HEDDEN, a citizen of the United States, and residing at Corral, in the county of Camas and State of Idaho, have invented certain new and useful Improvements in Extension-Sweep Bit-Braces, of which the following is a specification.

This invention relates to boring tools, and 10 it relates more particularly to an improved form of boring tools.

One of the objects of this invention is to provide a brace which is capable of having the arms shortened or lengthened; that is, 15 adjusted to various lengths of swing.

Another object is to provide a device of this character which is as strong, rigid and effective as a brace of unadjustable construction.

20 Another object is to provide a device of this kind which is so simple of construction that it may be manufactured and sold at a comparatively low cost.

Another object is to provide a device of 25 this character which may be very quickly disassembled; that is, separated into several distinctive elements which may be packed into a comparatively small space in a tool chest or the like.

30 Other objects and advantages may become apparent to persons who read the following detailed description in connection with the accompanying drawings in which:

Figure 1 is a side elevation view of the 35 complete brace.

Fig. 2 is an enlarged fragmental sectional view, illustrating the internal construction of the upper joint wherein the adjustments are made.

40 Fig. 3 is an enlarged bottom plan view of a portion of the upper lever or arm.

Fig. 4 is a top plan view of the upper end of the middle lever or member, and is identical with a bottom plan view of the lower 45 portion of said middle member.

Fig. 5 is a vertical transverse section taken on the line 5-5 of Fig. 2.

Fig. 6 is a horizontal section taken substantially along the line 6-6 of Fig. 2 as 50 viewed in the direction of the arrow, the parts being shown in their operative position.

Fig. 7 is a view similar to Fig. 6 except that the parts are shown in their extended 55 position and

Fig. 8 is a detailed view illustrating one

of the combined keepers and detents in three different elevations.

Referring to these drawings in detail in which similar reference characters correspond with similar parts throughout the several views, the device consists generally of three sections or separable elements A, B and C. (See Fig. 1.) The elements A and C are counterparts in all respects except that A is provided with the usual head or handle 10, while the element C may be provided with any ordinary or preferred type of chuck or tool holding element 11.

The element B is provided with the usual handle 12, which is rotatably mounted on a substantially U-shaped bar or crank element 13, the latter being provided at each end with a disk 14 having notches 15 and 16 formed in its periphery. There may be any 70 convenient number of notches 15, and they may be either equi-spaced as substantially shown in Fig. 4, or they may be spaced otherwise, according to particular desires or requirements, and these notches, which will hereinafter be known as "blind notches" 75 extend only a part of the way through the respective disks 14, as clearly shown in Figs. 1 and 2; but I preferably provide but two of the notches 16, and these notches extend 80 entirely across the cylindrical faces of the respective disks 14, as clearly shown in Figs. 1 and 4. The disks 14 are each provided with a central bore 17 for receiving a 85 pivotal element which will hereinafter be 90 described.

As the upper and lower connections are identically the same, the description of one joint or connection will suffice for both. The ends having the members 10 and 11 95 thereon will be hereinafter known as the outer ends, and the opposite ends of the elements A and C will be known as the inner ends. The inner end portion of each element A and C is detailed more clearly in 100 Fig. 3 in which 18 designates a broadened portion. A recess 22 is formed in the inner face of the part 18 and is intersected by a groove or slot 21 formed in the portions 19 and 20 on opposite sides of the widened portion 18. An opening 23 is formed in the part 18 to receive an operating member 33. The slot 21 may be either in the form of a dovetail, or it may be T-shaped as shown in Figs. 2, 3 and 5. In other words, the 110 slot 21 is broadened to provide shoulders or retaining elements 24. A pair of combined

keepers and detents 25 such as are more clearly shown in Fig. 8, are mounted to slide respectively in the grooves 21, and these sliding elements constitute clamp members and are each substantially T-shaped, that is, provided with heads or shoulders 26 for sliding engagement with the shoulders 24; so as to effectually prevent relative movement of the members 20 and 25, except the longitudinal movement above mentioned.

Within the recess 22 is seated an actuator or rotary disk or element 27 having a pair of diametrically spaced recesses 28, so as to provide room and clearance for links 29, these links being pivoted at 30 and 31 to the disks 27 and members 25 respectively, as clearly shown in Figs. 6 and 7. The disks 27 are each provided with a square or otherwise non-cylindrical aperture 32 for the purpose which will herein-after appear.

For the purpose of operating the elements 25 and 27 so as to effect adjustment of the device, I provide a pair of handle members or manipulative elements 33, each comprising a thumb piece 34, a boss or shoulder 35, a cylindrical or pivotal portion 37, (the latter being of smaller diameter than the former) and a non-cylindrical portion 38.

When the parts of the bars are assembled and in the operative relation shown in Figs. 1, 2 and 6, the non-cylindrical element 38 is seated in the non-cylindrical recess 32 of the disk 27, while the cylindrical portions 36 and 37 are formed to rotate in the apertures 23 and 17 respectively. A pin 39 or other suitable means may be employed for securing the portion 38 in the aperture 32 of the disk 27, and this prevents the manipulative member 33 from being accidentally displaced, while the several portions of the manipulative member 33 co-operate with the members 25 and 29 in preventing accidental movement of the elements A, B and C with relation to one another. In order to effect this co-operation, the members 25 are each provided with a detaining lug 40, a retaining lug or keeper element 41 and a notch or recess 42. The detaining lugs 40 normally engage with the notches 15 so as to prevent accidental rotation with relation to the disks 18 and arms 20, while the retaining lugs 41 engage with the plane outer surface of the respective disks 14 and prevent axial movement of the disks with respect to the pivot elements 36 and 37.

In adjusting the device, the manipulative elements 33 are rotated through a suitable arc for moving the members 25 from the position shown in Figs. 2 and 6 to the position shown in Fig. 7. This movement brings the detaining portions 41 in engagement with the disks 14. It will be seen, therefore,

that the disks 14 may now be rotated about their respective pivotal elements 37, and that in thus rotating the disks, the handle element 12 is adjusted with relation to the members 10 and 11, the amount of adjustment being determined by the notches 15 in which the detents 40 rest when the adjustment is effected.

In order to hold the members 25 in their operative position, I provide a spring 43, which is here illustrated as a compression spring and which is seated between the inner end of the slot 21 and the side of the detaining member 25. By holding one of the members 25 in the notch 15, this member co-operates with the disk 27 and the connected links 29 for holding the companion member 25 in its notch 15.

Although I have described this embodiment of my invention in minute detail, it is to be understood that my invention is not limited to these exact details of construction and arrangement of parts, but that I am entitled to make such changes that do not constitute a departure from the invention disclosed.

What I claim as my invention is:

1. In a bit brace comprising relatively upper and lower arms, a handle member having crank portions at its ends terminating in disks, clamp members slidably mounted on the arms and adapted to engage the disks at opposite points and secure the handle member in an adjusted position, and operating means for the clamp members mounted on the arms.

2. In a bit brace comprising relatively upper and lower arms, a handle member having crank portions at its ends terminating in disks, clamp members slidably mounted on the arms and adapted to engage the disks at opposite points, and secure the handle member in an adjusted position; operating members rotatably mounted on the arms and engaging the said disks centrally, and connecting means between the operating members and the clamp members to effect a sliding of the clamp members and adapted to hold them in clamping position.

3. In a bit brace comprising relatively upper and lower arms, a handle member having crank portions at its ends terminating in disks, clamp members slidably held on the arms and disposed on opposite sides of the disks, operating members rotatably mounted on the arms and engaging the disks centrally, and link connections between the operating members and the clamp members.

4. A bit brace comprising an upper lever and a lower lever each formed with a longitudinal substantially dovetailed slot, a pair of keeper members mounted for sliding movement longitudinally of said slot, an intermediate member provided with a han-

dle and with a notched disk at each end, each notched disk being pivotally connected to a respective one of said levers and disposed between the keeper members thereof, 5 and means co-operative with said keeper members for retaining said intermediate member in different adjusted positions with relation to said levers.

5. A bit brace comprising an upper lever 10 and a lower lever each provided with a longitudinal and substantially dovetailed slot, keeper members each mounted to slide longitudinally in a slot of one of said levers, an actuating member connected thereto for 15 operating said keeper member, manipulative members each pivotally connected to one of said levers and secured to said actuating member and being provided with a pivotal

portion extending beyond said actuating member, and an intermediate member having each end provided with a notched disk having a central bore therein for receiving said pivotal portion, each of said disks being connected to one of said levers by means of said manipulative member and 20 said keeper member, said keeper member being movable by means of said manipulative member and actuating member for causing said keeper member to engage selected notches of said disk. 25

In testimony whereof I affix my signature in presence of two witnesses.

CLARENCE D. HEDDEN.
